UNITED STATES PATENT OFFICE.

PAUL SIPTROTT, OF NEW YORK, N. Y., ASSIGNOR TO CONSOLIDATED ART METAL FOUNDRY, INC., A CORPORATION OF NEW YORK.

DESIGN FOR A LIGHTING-FIXTURE PART.

Application filed February 24, 1925. Serial No. 12,470. Term of patent 7 years.

To all whom it may concern:

Be it known that I, PAUL SIPTROTT, a citizen of the German Republic, and a resident of the city of New York, county and State of New York, have invented a new, original, and ornamental Design for Lighting-Fixture Part, of which the following is a specification, reference being had to the accompanying drawing, forming a part thereof.

Figure 1 is an inverted plan view of the

lighting-fixture part, the part shown in full line outline being ornamental in the same manner as the part more fully illustrated.

Figure 2 is a side elevation of the lighting-fixture part, the part shown in full line outline being ornamental in the same manner as the part more fully illustrated.

I claim:

The ornamental design for a lighting-fixture part as shown and described.

PAUL SIPTROTT.
